FEEDING AND COLD DRAWING MECHANISM

Lee Berkebil, Detroit, Mich., assignor to B. W. Manufacturing Company, Detroit, Mich., a corporation of Michigan

Original application June 27, 1938, Serial No. 216,134. Divided and this application May 8, 1939, Serial No. 272,506

17 Claims. (Cl. 205—3)

This invention relates generally to combined feeding and cold drawing mechanisms for heading machines and the like and constitutes a division of my application filed June 27, 1938, bearing Serial No. 216,134.

One of the essential objects of the invention is to provide an improved means for actuating a reciprocating feeding mechanism for the stock.

Another object is to provide such actuating means with adjustable means capable of providing equalized draft through the actuating means on the stock feeding mechanism.

Other objects, advantages and novel details of construction of this invention will be made more apparent as this description proceeds, especially when considered in connection with the accompanying drawings, wherein:

Figure 1 is a sectional plan view of a heading machine to which my improvements are applied;

Figure 2 is a side elevation of the feeding mechanism;

Figure 3 is a vertical central longitudinal section therethrough;

Figures 4 and 5 are diagrams illustrating the operating and timing mechanism.

Referring now to the drawings, A is the bed or frame, and B is a reciprocating head of a heading machine. As shown, the head B slidably engages ways C and is actuated by a crank or eccentric D on the main driving shaft E, through the medium of a connecting rod F. On the head B is mounted a vertically reciprocating slide B' which carries a plurality of heading dies B², B³. The stock for forming the blanks is advanced in a plane laterally offset from the plane of the dies B², B³. It is then cut off in predetermined lengths and the blanks thus formed are transferred into the plane of the dies to be successively operated upon thereby. The mechanism for accomplishing these functions includes a gear wheel G on the shaft E which drives an intermeshing gear wheel G' in a 1 to 2 ratio. The gear wheel G' is upon a shaft G² which extends transversely of the bed parallel to the shaft E. At opposite ends of the shaft G² are variable throw cranks G³ and G⁴; the one for operating the stock feeding mechanism, and the other for operating the blank shearing and transfer mechanism. There is also a cam G⁵ on the shaft G² which operates a mechanism for actuating the slide B' so as to alternately place the dies B² and B³ in registration with a cut-off blank in its transferred position. More

in detail and as shown in Figure 4, the crank G³ is provided with a crank pin H, which is adjustable radially in a slot H' to increase or diminish the throw thereof. A rod H² connects this crank pin with an adjustable pin H³ on the lever H⁴ for oscillating a gear wheel I, the arrangement being such that for two revolutions of the crankshaft E one revolution is imparted to the crank G³. Also, the length of the arc through which the gear wheel I is oscillated may be varied by adjustment of the crank pins H and H³. This gear wheel forms a part of my improved stock feeding and drawing mechanism which will be hereinafter described.

The crank G⁴ is connected by a rod J with a slide J' which has a cam slot J² engaging a pin J³ on a transversely movable slide J⁴. The slide J⁴ actuates the shearing and transfer member J⁵ as will be later described.

The mechanism for operating the slide B' is shown in Figure 5 and comprises a slotted member K slidably mounted on a bearing K' on the shaft G² and reciprocated by the cam G⁵ which engages rollers K² on said member K. The member K is connected to a rock arm K³ on a rockshaft K⁴, which extends transversely of the bed and has a rock arm K⁵ connecting the same with the slide B'. The cam G⁵ is so fashioned as to intermittently actuate this mechanism to raise and lower the slide B' with a dwell at each end of the movement thereof.

Connected to the bed A and arranged in a vertical plane which is laterally offset from the plane of the dies B², B³ is a frame L. This frame is formed in several sections including a central die-holding section L' and sections L² and L³ on opposite sides thereof which constitute slideways for stock feeders. The outer end of the frame is also floatingly supported by a pivotal link member L⁴ which rises from a supporting base L⁵. The stock is advanced through the frame L in a direction from left to right, Figures 1, 2 and 3, and for convenience in description, I will designate the portion to the right as forward and that to the left as rear.

Extending across the bed A and the forward end of the frame L are a pair of shafts M and M' which are in the same vertical plane and are connected to each other at one end by the intermeshing gear wheels I and I' fixed to the respective shafts. In central alignment with the frame L are rock arms M² which are connected by links M³ with a sliding head N forming the forward feeder. As this feeder has heavy work to perform it is quite essential that the links M³

should be properly aligned so that the direction of pull will be parallel to the slideways and with no tendency to tilt the slide N therein. Inasmuch as the shafts M and M' are driven through the medium of intermeshing gear wheels, it is necessary that the rock arms M² should be very accurately positioned on said shafts to produce this parallel movement of the links M² and head N. This is accomplished by first connecting each rock arm to its shaft through the medium of a key M⁴ having a wide portion M⁵ engaging the keyway in the rock arm and a narrow right angularly extending portion M⁶ engaging a keyway in the shaft. Thus by reversing the key M⁴ the rock arm will be circumferentially adjusted upon the shaft a distance equal to the variation in widths of the portions M⁵ and M⁶. Further and more accurate angular adjustment is accomplished by forming the rock arm in two sections embracing the shaft and connected to each other by clamping screws M⁷. Sufficient clearance is provided between the adjacent faces of these sections, so that by loosening one screw and tightening the other, one section may be angularly adjusted with respect to the other. The section which has the pivot pin M⁸ connecting with the link M² is the adjustable section, while the other section contains the key M⁴ for attachment to the shaft. Thus by means of these two adjustments the required accuracy and positioning of the rock arms may be accomplished.

The slide head N of the forward feeder has spaced upper and lower portions forming wedge surfaces N' which taper from forward to rear. These portions are held in rigid relation to each other by side plates N² and splines (not shown). N⁴ are clamping jaws within the recess and having their outer surfaces parallel to the surfaces N' with rollers N⁵ arranged therebetween. The jaws N⁴ embrace the stock which is to be fed and during the forward movement of the head N the resistance or load will tend to draw the jaws rearward, thereby wedging the same to tightly grip the stock. On the other hand, when the member N is moved rearward, this will instantaneously release pressure on the jaws so as to permit the same to slide rearward over the stock. Springs N⁶ within the recess and bearing against the forward ends of the jaws will hold the same in frictional engagement with the stock. There are also bushings N⁷ and N⁸ in the sliding head N for guiding the stock passing therethrough.

The intermediate section L' holds the die member O through which the stock is passed to slightly reduce the diameter and finish the surface thereof.

Inasmuch as the feeder N is forward of the die O, it is obvious that some additional means must be provided to advance the forward end of the stock through the die before it can be engaged by said feeder. For this purpose I have provided a second feeder P which is substantially the same in construction as the feeder N and, therefore, will not be described in detail. This second feeder is actuated by the feeder N through the medium of rods P'. The forward ends of these rods threaded engage the head N and extend rearward therefrom through apertures in the walls O² and O³ into the section L² of the frame L. The rear ends of these rods are also threaded and have engaged therewith correspondingly threaded sleeves P² which form shoulders that may be adjusted into different positions. A screw P³ engaging the rear portion of

the sleeve P² and bearing against the rod P' serves to lock these members in any desired position of adjustment. The rods P' also pass through channels in the feeder P, and springs P⁴ sleeved on the rods forward of the feeder P yieldably press said feeder rearward toward the limiting stops formed by the sleeves P².

The bushings N⁹ and N¹⁰ for the feeder N may be selected with respect to the diameter of stock to be passed therethrough, and similar bushings are provided for the feeder P which are of a diameter corresponding to that of the stock before it passes through the sizing die O. Still another bushing S is mounted at the rear end of the frame L and the stock is first fed through this bushing and into operative relation to the jaws of the rear feeder P.

What I claim as my invention is:

1. In a machine of the character described, a frame, means for advancing the stock slidably mounted in said frame, a pair of shafts extending transversely of said frame on opposite sides of the stock, rock arms on said shafts, rods connecting said rock arms to said stock advancing means, means for oscillating one of said shafts, gearing between said shafts for effecting the simultaneous oscillation thereof, and means for adjusting at least one of said rock arms on its shaft to align the same with the other rock arm whereby the draft through said rods on said stock advancing means is equalized, said adjusting means including a reversible key having a wide portion engaging a keyway in the rock arm and having a narrow right angularly extending portion engaging a keyway in the shaft.

2. In a machine of the character described, a frame, means for advancing the stock slidably mounted in said frame, a pair of shafts extending transversely of said frame on opposite sides of the stock rock arms on said shafts, rods connecting said rock arms to said stock advancing means, means for oscillating one of said shafts, gearing between said shafts for effecting the simultaneous oscillation thereof, and means for adjusting said rock arms on their respective shafts comprising spaced bearing members for engaging each shaft, one being integral with each rock arm, a reversible spline for connecting the other bearing member to each shaft, said spline having a narrow portion engaging the shaft and having a wide right angularly extending portion engaging the bearing, whereby reversal of said spline effects adjustment of the rock arm, and an adjustable screw connection between the two members of the bearing for effecting further adjustment therebetween.

3. In a machine of the character described, a frame, means slidably mounted in the frame for advancing the stock, a pair of shafts carried by the frame, rock arms on said shafts, means connecting said rock arms to said stock advancing means, means for oscillating one of said shafts, means for imparting such oscillating motion to the other of said shafts, and two means for aligning said rock arms on said shafts so that the draft through said connecting means on the stock-advancing means is equalized, one of said aligning means comprising reversible keys substantially L-shape in cross section engaging keyways in said shafts and rock arms.

4. In a machine of the character described, a frame, stock advancing means including a head slidably mounted on the frame and stock engaging jaws carried by said head, a pair of shafts carried by the frame, rock arms on said shafts,

5 rods connecting said arms to said head, means for oscillating one of said shafts, means for imparting such oscillating motion to the other of said shafts, and two means for aligning said arms on said shafts so that the draft through said rods on the head is equalized, one of said aligning means including reversible keys substantially L-shape in cross section engaging keyways in said shafts and rock arms.

10 5. In a machine of the character described, a frame, stock advancing means including a head slidably mounted on the frame and stock engaging jaws carried by said head, a pair of shafts carried by the frame, rock arms on said shafts, means connecting said arms to said head, means for oscillating one of said shafts, means for imparting such oscillating motion to the other of said shafts, and two means for aligning said arms on said shafts so that the draft through said connecting means on the head is equalized, one of said aligning means including reversible keys substantially L-shape in cross section engaging keyways in said shafts and rock arms.

15 6. In a machine of the character described, a frame, stock advancing means including a head slidably mounted on the frame and stock engaging jaws carried by said head, a pair of shafts carried by the frame, rock arms on said shafts, rods connecting said arms to said head, means for oscillating one of said shafts, means for imparting such oscillating motion to the other of said shafts, and two means for angularly adjusting at least one of said rock arms on its shaft to align the same with the other rock arm whereby the draft through said rods on said stock advancing means is equalized, one of said aligning means including reversible keys substantially L-shape in cross section engaging keyways in said shafts and rock arms.

20 7. In a machine of the character described, a frame, means carried by said frame for advancing the stock, a pair of shafts carried by said frame, rock arms on said shafts, rods connecting said rock arms to said stock advancing means, means for oscillating one of said shafts, a driving connection between said shafts, and two means for adjusting at least one of said rock arms on its shaft to align the same with the other rock arm whereby the draft through said rods on said stock advancing means is equalized, one of said means including reversible keys of L-cross section engaging keyways in said shafts and rock arms.

25 8. In a machine of the character described, a frame, means carried by said frame for advancing the stock, a pair of shafts carried by said frame, rock arms on said shafts, rods connecting said rock arms to said stock advancing means, means for oscillating one of said shafts, gearing between said shafts for effecting the simultaneous oscillation thereof, and means for adjusting said rock arms on their respective shafts comprising spaced bearing members for engaging each shaft, one being integral with each rock arm, a spline for connecting the other bearing member to each shaft, having the portion engaging the shaft substantially at right angles to the portion engaging the bearing, whereby reversal of said spline effects adjustment of the rock arm.

30 9. In a machine of the class described, a frame, stock advancing means carried by said frame, a pair of shafts, intermeshing gears on said shafts, and rock arms on said shafts, each arm having cooperating bearing sections engag-

5 ing its shaft, one section of each rock arm being adjustably keyed to its shaft, the other section of each rock arm being adjustably connected to the keyed section and being connected to said stock advancing means.

10 10. In a machine of the class described, a frame, stock advancing means including a head slidably mounted on the frame, a pair of shafts carried by the frame, intermeshing gears fixed to said shafts, and rock arms on said shafts and connected to said head, at least one of said rock arms being adjustable on its shaft to align the same with the other rock arm so that the draft on said head is equalized, and a reversible key of substantially L-cross section connecting the other of said rock arms to its shaft.

15 11. In a machine of the class described, a sizing die, a reciprocating feeder for moving stock through said die, and actuating means for said feeder including a pair of shafts extending transversely to the path of movement of the feeder, a driving connection between said shafts, sectional rock arms mounted on said shafts, and links terminally connected to said feeder and rock arms, the mountings for said rock arms including adjustments for said arms relative to said shafts and adjustments for the respective sections relative to each other.

20 12. In a machine of the class described, a frame, a die for sizing stock carried by said frame, a reciprocating feeder for causing stock to be moved through said die, slideways for said feeder carried by said frame, and means for reciprocating the feeder in a direction substantially parallel to the slideways with substantially no tendency to tilt relative thereto, including a pair of shafts extending transversely to the path of the feeder, said shafts being substantially in the same vertical plane and connected to each other at one end, sectional rock arms mounted on said shafts substantially in central alignment with said frame, and links terminally connected to said feeder and rock arms, the mountings for said rock arms including adjustments for said arms relative to said shafts and adjustments for the respective sections relative to each other.

25 13. In a machine of the class described, a frame, a die for sizing stock carried by said frame, a reciprocating feeder for causing stock to be moved through said die, slideways for said feeder carried by said frame, and means for reciprocating the feeder in a direction substantially parallel to the slideways with substantially no tendency to tilt relative thereto, including a pair of shafts extending transversely to the path of the feeder, said shafts being operatively connected to each other, sectional rock arms mounted on said shafts substantially in central alignment with the frame, and links terminally connected to said feeder and rock arms, the mountings for said rock arms including reversible key adjustments for said arms relative to said shafts and screw adjustments for the respective sections relative to each other.

30 14. In a machine of the class described, a frame, a die for sizing stock carried by said frame, a reciprocating feeder for causing stock to be moved through said die, slideways for said feeder carried by said frame, and means for reciprocating the feeder in the slideways, including a pair of shafts extending transversely to the path of the feeder and operatively connected to each other, sectional rock arms mounted on said shafts, and links terminally connected to said feeder and rock arms, the mountings for said

- rock arms including adjustments for said arms relative to said shafts and adjustments for the respective sections relative to each other.
15. In a machine of the class described, a frame, a die for sizing stock carried by said frame, a reciprocating feeder for causing stock to be moved through said die, slideways for said feeder carried by said frame, and means for reciprocating the feeder in the slideways, including a pair of shafts extending transversely to the path of the feeder, said shafts being operatively connected to each other, sectional rock arms mounted on said shafts, and links terminally connected to said feeder and rock arms, the mountings for said rock arms including reversible key adjustments for said arms relative to said shafts and screw adjustments for the respective sections of said rock arms.
16. In a machine of the class described, a sizing die, means for moving stock through said die, and actuating means for said moving means including a pair of substantially parallel shafts

extending transversely to the path of the stock moving means, a driving connection between said shafts, sectional rock arms mounted on said shafts, and links terminally connected to said moving means and rock arms, the mountings for said rock arms including adjustments for said arms relative to said shafts and adjustments for the respective sections relative to each other.

17. In a machine of the class described, a sizing die, means for moving stock through said die, and actuating means for said moving means including a pair of substantially parallel shafts extending transversely to the path of the stock moving means, a driving connection between said shafts, sectional rock arms mounted on said shafts, and links terminally connected to said moving means and rock arms, the mountings for said rock arms including reversible key adjustments for said arms relative to said shafts and screw adjustments for the respective sections of the rock arms.

LEE BERKEMIL.
